UNITED STATES PATENT OFFICE.

BENJAMIN WEXLER, OF BROOKLYN, NEW YORK, ASSIGNOR TO THE PEELLE COMPANY, OF BROOKLYN, NEW YORK, A CORPORATION OF NEW YORK.

EXPANSION SHOE FOR ELEVATOR DOORS.

1,416,247.

Specification of Letters Patent. Patented May 16, 1923.

Application filed September 1, 1921. Serial No. 497,470.

To all whom it may concern:

Be it known that I, BENJAMIN WEXLER, a citizen of the United States, residing at the borough of Brooklyn, in the city of New York, county of Kings, and State of New York, have invented certain new and useful Improvements in Expansion Shoes for Elevator Doors, of which the following is a specification, reference being had therein to 10 the accompanying drawing, which forms a part thereof.

My invention relates to expansion shoes for elevator doors, and more particularly to a type thereof adapted for use in fireproof 15 elevator doors.

Heretofore in this art, it has been a common practice to provide expansion guide members upon the side rails or bars of the metallic frame of a fireproof elevator door, 20 such a guide member being shown in Letters Patent No. 1,237,430 granted to me under date of August 21st, 1916. In this type of guide member, a portion of the flame angle carried by each side rail or bar of the 25 frame of the door had a slit cut so as to permit a portion of one flange of this flame angle to be bent outwardly toward the wall rail so that in the event of expansion of the frame of the door under heat, this guide 30 member will yield under the lateral stresses and thus prevent the binding of the door between the guides to an extent which will prevent the operation of the door in the event of fire. Said guide member is held 35 against displacement with relation to the side bar by suitable means.

The construction shown in my aforesaid Letters Patent, while meeting the requirements for which it was intended, has not 40 been found entirely satisfactory in use, since in the ordinary functioning of the door, it is guided in its movement through its co-operation with the flanges of the wall angle and with a guide angle secured thereto, be- 45 tween the inwardly projecting flange of which and the parallel flange of the wall angle, said member has movement. This condition not only necessitates a special construction of the guides for the elevator 50 doors, but entails considerable difficulty when mounting these rails, and under or-

dinary conditions results in excessive clearance between the guide and the rails tending toward looseness in the panels of the doors under normal conditions of use. 55 Furthermore, guide members formed integrally with the flame angle of the door entail considerable difficulty in their production, and are subject to disarrangement of parts during shipping and installation 60 of the doors, as well as during their use.

With the above conditions in mind, I have produced an expansion shoe which, when applied to a door, while co-operating with a standardized rail structure, and functioning as a guide shoe in the same manner and with as close a fit as guide shoes of a non-expansive type, is capable of having movement relative to the door in the event of expansion of the door under heat, so as to prevent binding of the shoes upon the guides or a displacement of the guides by the door, in the event of fire. 70

While a shoe embodying my invention under normal working conditions is substantially rigid, it is slidably mounted upon the flame angle of the door and provided with supporting members collapsible when subjected to stresses resulting from expansion of the door. 80

The manner of slidably mounting the shoe upon the flame angle is such that in the event of the collapse of its supports, it will recede toward the door with a rectilinear movement so as to minimize any tendency toward a binding of the shoes between the guide rail and the supports for the shoe. 85

The invention consists primarily in an expansion shoe for elevator doors embodying therein a forked member adapted to 90 straddle the guide rail for a door, a flame angle carried by the door, means whereby said forked member is slidably mounted upon said flame angle, and a collapsible support for said member bearing against 95 the side of the door, whereby in the event of expansion of the door from heat, the stresses developed will collapse said support and permit said shoe to have movement on the flame angle towards the door; and 100 in such other novel features of construction and combination of parts as are hereinafter

set forth and described, and more particularly pointed out in the claims hereto appended.

Referring to the drawings,

5 Fig. 1 is a condensed elevation of a pair of elevator doors embodying my invention;

Fig. 2 is a horizontal section of one side of one of said doors, showing a shoe embodying my invention in elevation;

10 Fig. 3 is a front view thereof; and

Fig. 4 is an enlarged view similar to Fig. 2, showing the construction of the shoe and the co-operating wall and guide angles.

Like letters refer to like parts throughout
15 the several views.

In the embodiment of my invention shown in the drawings, *a* indicates the upper, and *b* the lower panel of a pair of vertically movable panels of a door embodying my invention, which panels are connected by the suspension means *c* to have simultaneous vertical movement in opposite directions. A multiple panel door is shown because this type of door is more extensively used than
20 a single panel door, although my invention is equally applicable to the latter type of door.

Mounted upon opposite sides of the various door openings in the shaft, is a vertically extending wall angle *d*, one flange of which is attached to the wall of the shaft and the other flange of which extends inwardly at right angles to said wall. Secured to the last named flange of the wall angle is a guide angle *e*, one flange of which is used for securing it to the flange of the wall angle, and the other flange of which extends parallel with the wall and serves as a guide rail for the elevator doors.

40 Elevator doors of the type to which my invention relates are formed of an angle metal frame *f* constituting the oppositely disposed parallel top and bottom rails of the door and the vertical side rails thereof, the opening in this frame being closed either by a metal sheathed, wooden panel or by a corrugated metal panel.

Such doors are used extensively in connection with elevator equipment of warehouses and are of large dimensions, so that in the event of fire the heating of the frame will have a tendency to materially expand same, the expansion of the top and bottom rails resulting in a sufficient enlargement of the lateral dimensions of the door, so that if the guide shoes carried thereby have a sufficiently close fit with the guide rail *e*, to normally insure free movement of the door, without looseness, this expansion will result in a binding of the door which will
55 make its operation difficult if not impossible.

To avoid this condition, as well as to ensure a smooth running of the door under normal conditions, a shoe embodying my invention is used.

Secured to each side rail of a door panel is a flame angle formed by a vertically extending angle bar *g*, one flange *g'* of which extends between the guide rail and the parallel flange of the wall angle, so as to effectively close any gap at opposite edges of the door to prevent the escape of flames and smoke from the floor of the building to within the shaft, or vice versa.

Carried by the flange *g'* of at least one of said flame angles *g* are a plurality of shoes embodying my invention, said shoes consisting of a forked member *h* substantially corresponding in dimensions and configuration with the guide shoes commonly used upon doors of this type, except as to the manner of mounting same with relation to the door. This forked member is adapted to straddle the guide rail *e* and have a sufficiently close fit therewith to avoid excessive movement of the door transversely of the guide rail and laterally of the door opening, while ensuring the smooth running of the door under normal working conditions.

Said member *h* is slidably mounted upon the flange *g'* of the flame angle *g* by means of slots *h'-h²*, which slots extend substantially horizontally and receive the bolts *i-i'*, said slots being formed in extensions of the arm of the forked member *h* positioned between the guide rail *e* and the wall angle *d*. Said extensions are reduced in thickness so as to position the heads of the bolts or rivets *i-i'* out of a plane of contact with the guide rail *e*.

Disposed between the forked member *h* and the flange *g'* of the flame angle *g* is a suitable gasket *j* of paper, fusible metal or other material which, if subjected to heat, will disintegrate sufficiently to ensure freedom of movement of the member *h* with relation to its supporting bolts or rivets and the flange *g'*.

In addition to the slots *h'-h²* and the co-operating bolts or rivets *i-i'*, the member *h* is secured with relation to the door frame to the flame angle *g*, by means of collapsible supports *k-k'* which will engage the flange *g'* of the flame angle secured to the side rail of the door section.

Under normal conditions looseness of the shoe is prevented by so proportioning the length of the slots *h'-h²* that the bolts or rivets *i-i'* will engage the end thereof adjacent to the door and thus hold the supports *k-k'* in the desired intimate engagement with the said flame angle flange.

It is apparent that the particular construction of flame angle shown in the drawing, need not be employed, and that the supports *k-k'* will have exactly the same operative effect if they engage the side bar of the door directly instead of through the medium of the flange of the flame angle.

Any desired number of shoes may be se-

cured to the side rail of the door, preferably two shoes being ordinarily used.

While the use of expansion shoes upon one side only of the door, would avoid binding of the door in case of expansion as a result of fire, it is generally required, and preferable, to apply such shoes to the opposite side of the door, which, however, merely involves a duplication of parts.

10 The operation of the herein described shoe is substantially as follows:—

In elevator doors embodying expansion shoes made in accordance with my invention, the shoes may be attached to the doors in the factory, or shipped to the point of installation separate from the door structure. If the latter practice be followed, the flame angle will be pierced at the proper points to receive the bolts or rivets $i-i'$ thus facilitating the assembling of the door structure, while the door is being installed, since this involves merely the mounting of the forked member h upon the flame angle g , the dimensions of the collapsible supports $k-k'$, being such as to ensure the proper locating of the slot $h'-h^2$ with relation to the rivet openings in said flame angle.

It is the common practice to provide the guide rail structures for fire proof elevator doors with removable sections to facilitate the mounting and removal of doors from the guide rails.

In the event of wear upon the expansion shoe of my invention, such removable sections of the guide rail may be used to permit a rapid and convenient removal of a worn shoe and the substitution of a new shoe therefore.

The gasket j between the member h and the flame angle and the location of the bolts or rivets $i-i'$ at the end of the elongated slots $h'-h^2$, towards this door section will ensure the desired firm seating of the member h while permitting looseness of said member in the event of the destruction of the gasket when subjected to high temperatures.

Under normal conditions, the member h will function solely as a guide shoe the reduced extensions of the inner arm of the forked member so positioning the bolts or rivets $i-i'$ as to prevent such contact thereof with the rail, as might interfere with the free running of the door.

55 In the event of the expansion of the door frame under heat, the collapsible supports $k-k'$ will yield before the application of stresses to the guide rail e , will be sufficient to permit a material binding of the shoe against same, or distortion of the guide rail. To secure this result, it is apparent that the supports $k-k'$ must be so proportioned as to give them a lower compression co-efficient than that of the wall and guide rail structure.

With the destruction or disintegration of the gasket j from heat and the collapse of the supports $k-k'$, this member h may slide freely upon the bolts or rivets $i-i'$, the parallel relation of the slots $h-h'$ preventing any skewing of this member h . The resultant rectilineal movement of said fitting will prevent possible jamming of the door so that even if the supports $k-k'$ were to be collapsed otherwise than as a result of expansion of the door the only result would be lost motion laterally of the door, since the depth of the fork of the member h would prevent disengagement of the shoe from its rail even upon a maximum collapsing of the said supports.

If any fitting of the shoe be required, the use of material stock permits a workman to collapse or extend the supports $k-k'$ by the use of a hammer, the slots $h'-h^2$ permitting sufficient variation in the position of the member h , upon the flame angle to secure any desired adjustment of the shoe with relation to the guide rail e .

The manner of mounting the guide shoe upon the flame angle avoids the presence of any gaps in this flame angle, while permitting the desired relative movement of the shoes and the door structure in the event of fire.

95 The member h and the parts appurtenant thereto may be readily made of malleable metal, thus ensuring substantial uniformity in the dimensions of all shoes, and obviating any nicety in the fitting of the shoes to the door or to the guide rail.

It is not my intention to limit the invention to the precise details of construction shown in the drawing, it being apparent that such may be varied without departing from the spirit and scope of the invention.

Having described the invention, what I claim as new, and desire to have protected by Letters Patent is:—

1. An expansion shoe for elevator doors, embodying therein a forked member adapted to straddle the guide rail for a door, a flame angle carried by the door, means whereby said forked member slidably is mounted upon said flame angle, and a collapsible support for said member bearing against the side of the door, whereby in the event of the expansion of the door from heat, stresses developed will collapse said support and permit said shoe to have movement on the flame angle towards the door.

2. An expansion shoe for elevator doors embodying therein a forked member adapted to straddle the guide rail for a door, a flame angle carried by the door, said forked member having a plurality of elongated slots therein, bolts carried by said flame angle projected through said slots and engaging said forked member adjacent said slots whereby said forked member is slidably

mounted upon said flame angle, and a collapsible support for said member bearing against the side of the door, whereby in the event of expansion of the door from heat, 5 the stresses developed will collapse said support and permit said shoe to have movement on the flame angle towards the door.

3. An expansion shoe for elevator doors embodying therein a forked member adapted 10 to straddle the guide rail for a door, a flame angle carried by the door, a gasket of material which will disintegrate when subjected to heat interposed between said forked member and said flame angle, means 15 whereby said forked member is slidably mounted upon said flame angle, and a collapsible support for said member bearing against the side of the door, whereby in the event of expansion of the door from heat, 20 the stresses developed will collapse said support and permit said shoe to have movement on the flame angle towards the door.

4. An expansion shoe for elevator doors embodying therein a forked member adapted 25 to straddle the guide rail for a door, a flame angle carried by the door, said member having a plurality of parallel horizontal elongated slots, bolts carried by said flame angle passing through said slots and engaging said 30 member adjacent thereto whereby said forked member is slidably mounted upon said flame angle, and a collapsible support for said member bearing against the side of the door, whereby in the event of expansion 35 of the door from heat, the stresses developed will collapse said support and permit said shoe to have rectilineal movement on the flame angle towards the door.

5. An expansion shoe for elevator doors 40 embodying therein a forked member adapted to straddle the guide rail for a door, a flame angle carried by the door, the arm of said forked member adjacent said flame angle being provided with extensions reduced in 45 thickness as compared with said arm and having elongated slots thereto, bolts carried by said flame angle and projecting through said slots and engaging the extension adjacent thereto whereby said forked member 50 is slidably mounted upon said flame angle, and a collapsible support for said member bearing against the side of the door whereby in the event of the expansion of the door from heat the stresses developed will collapse 55 said support and permit said shoe to have movement on the flame angle towards the door.

6. An expansion shoe for elevator doors 60 embodying therein a forked member adapted to straddle the guide rail for a door, a flame angle carried by the door, the arm of said forked member adjacent said flame angle

having extensions reduced in thickness as compared with the arm, and each an elongated slot therein, said slots being parallel, 65 bolts carried by said flame angle, projecting through said slots and engaging the extension adjacent thereto, whereby said member is slidably mounted upon said flame angle, and a collapsible support for said member 70 bearing against the side of the door whereby in the event of expansion of the door from heat, the stresses developed will collapse said support, and permit said shoe to have rectilineal movement on the flame angle towards 75 the door.

7. An expansion shoe for elevator doors embodying therein a forked member adapted to straddle the guide rail for a door, a flame angle carried by the door, the arm of said 80 forked member adjacent to said flame angle having extensions reduced in thickness as compared with the arm, and having an elongated slot therein, said slots being parallel with each other a gasket of material which 85 will disintegrate when subjected to heat interposed between said forked member and said flame angle, bolts carried by said flame angle projecting through said gasket and said slots and engaging the extensions adjacent thereto, whereby said member is slidably mounted upon said flame angle and a collapsible support for said member bearing against the side of the door whereby in the event of expansion of the door from heat, 90 the stresses developed will collapse said support and permit said shoe to have rectilineal movement on the flame angle towards the door.

8. An expansion shoe for elevator doors 100 embodying therein a member adapted to slidably engage the guide rail for an elevator door, means whereby said member is slidably mounted upon the flame angle of a door means normally preventing movement 105 of said member towards the door consisting of supports having a lower compression coefficient than the guide rail structure, and a gasket formed of material which will disintegrate under heat, interposed between 110 said member and said flame angle, whereby under normal conditions said shoe will have a substantially rigid relation to the door but will have movement toward the door as a result of the disintegration of said gasket 115 and the collapse of said support when the door is subjected to heat.

In witness whereof I have hereunto affixed my signature this 26th day of August, 1921, in the presence of two subscribing witnesses. 120

BENJAMIN WEXLER.
